UNITED STATES PATENT OFFICE.

EUGENE H. PECK, OF NEW YORK, N. Y., ASSIGNOR TO THE PHOENIX GLASS COMPANY
A CORPORATION OF WEST VIRGINIA.

DESIGN FOR A GLOBE.

50,208.

Specification for Design.

Patented Jan. 16, 1917.

Application filed November 1, 1916. Serial No. 129,026. Term of patent 7 years.

To all whom it may concern:

Be it known that I, EUGENE H. PECK, a citizen of the United States, residing at New York, in the county of New York and State of New York, have invented a new, original, and ornamental Design for Globes, of which the following is a specification, reference being had to the accompanying drawing, forming part thereof.

The figure is a side elevation of a globe, showing my new design.

I claim:

The ornamental design for a globe, as shown.

EUGENE H. PECK.
